UNITED STATES PATENT OFFICE.

ANTON MOLINARI, OF WOODRIDGE, NEW JERSEY.

SYRINGE.

SPECIFICATION forming part of Letters Patent No. 778,879, dated January 3, 1905.

Application filed July 27, 1904. Serial No. 218,813.

To all whom it may concern:

Be it known that I, ANTON MOLINARI, a citizen of the United States, residing at Woodridge, in the county of Bergen and State of New Jersey, have invented certain new and useful Improvements in Syringes, of which the following is a specification.

This invention relates to improvements in hypodermic syringes; and the object of my invention is to provide a new and improved syringe of this kind which is simple in construction, can readily be taken apart for cleaning and disinfecting and can readily be reassembled for use, and is not expensive.

In the accompanying drawings, in which like letters of reference indicate like parts in all the figures, Figure 1 is a vertical longitudinal sectional view of my improved syringe. Fig. 2 is a detail sectional view of a modified construction, parts being broken away.

The barrel A is made of glass and is provided at its upper end with an outwardly-extending flange B and at its lower end is provided with an inwardly-extending flange C, forming a central aperture D. An externally-threaded tubular nipple E, provided with a head F, is passed through the aperture D, and a washer G is placed against the under side of said head, which washer rests on the upper surface of the internal flange C. If desired, a washer H may be placed on the lower end of the barrel A around the threaded nipple E.

A cap J, adapted to receive the lower end of the barrel A, is provided with a central screw-threaded aperture I, into which the end of the nipple projecting beyond the end of the barrel can be screwed, so that when the said cap is screwed up tight the washer G is pressed upon the inner surface of the lower end of the barrel and the barrel drawn firmly into the cap J, and if the bottom washer H is used the same is firmly pressed against the lower end of the barrel A.

The piston-rod K is provided at its lower end with a head or annular flange L, on which the tubular piston-packing M, of cork, rubber, leather, asbestos, or other material, can rest, and the upper end of the piston-rod

is provided with the screw-threaded end N, 50 which can be screwed into the handle part O, which may be of any suitable shape—as, for example, is shown in full and dotted lines in Fig. 1. The piston-rod K is provided with the usual graduations, as shown.

A glass tube P, surrounding the piston-rod K, rests with one end upon the packing M, and on its upper end the lower end of the handle head or part O rests. When said handle head or part O is screwed down, it presses the glass tube P lengthwise, and this tube pressing on the packing M spreads the same more or less, as may be desired or necessary. The operator can thus at any time spread the packing as necessity may require.

The graduations on the piston-rod K can readily be read through the glass barrel and the glass tube P.

A hypodermic needle of any desired style, pattern, or make can be screwed on the projecting end of the nipple E.

To take the syringe apart, the cap J is first unscrewed. The nipple E and its head F are removed by reversing the barrel after the piston has been withdrawn, the washer H, in 75 case the same has been used, having been first withdrawn, the nipple and its head dropping out of the barrel. Then the handle part of head O is unscrewed from the piston-rod and the glass tube P and the packing M are removed from the piston-rod. All parts are thus separated and detached and can be cleaned and disinfected and can then be readily reassembled in the reverse order of the steps described above.

In case it is desired to attach handles or holding devices on the barrel an externally-threaded ring R is slipped on the barrel A from below until it rests against the top external flange B, and a cap S is screwed on this ring, the cap resting on the flange B. The cap has a hole T of sufficient size for the glass piston-tube P to pass through, but not the packing M when the latter is spread. Rings W or arms, the latter shown in dotted lines, project from the said cap S and serve for holding the barrel while forcing the piston in or out. After the cap S has been

unscrewed the ring R can be readily slipped off the barrel.

Having described my invention, what I claim as new, and desire to secure by Letters 5 Patent, is—

1. A syringe having a glass barrel, a needle-holding nipple held detachably within the end of said barrel and projecting beyond the end of the barrel, and means applied on the 10 outside of the barrel for holding said nipple in place, substantially as set forth.

2. In a syringe, the combination with a barrel having an inwardly-extending flange at its lower end, of a tubular nipple having a 15 head resting on the inner surface of the lower end of the barrel, the nipple projecting through the opening in the lower end of the barrel, and a cap embracing the lower end of the

barrel, through which cap said nipple is projected, substantially as set forth. 20

3. In a syringe, the combination with a piston-rod, having a head on its lower end, and having its upper end threaded, of a packing resting on said head, a tube surrounding the piston-rod and resting on said packing, and a handle-head screwed on the upper end of the piston-rod and resting on said tube, 25 substantially as set forth.

In testimony whereof I have signed my name to this specification, in the presence of 30 two subscribing witnesses, this 17th day of March, 1904.

ANTON MOLINARI.
